US0D1007518S

(12) **United States Design Patent** (10) Patent No.: **US D1,007,518 S**
Pillalamarri et al. (45) Date of Patent: **** Dec. 12, 2023**

(54) **DISPLAY SCREEN WITH A GRAPHICAL USER INTERFACE**

(71) Applicant: **INSULET CORPORATION**, Acton, MA (US)

(72) Inventors: **Sandhya Pillalamarri**, Methuen, MA (US); **Jorge Borges**, Billerica, MA (US); **Susan Mercer**, Waltham, MA (US)

(73) Assignee: **INSULET CORPORATION**, Acton, MA (US)

(**) Term: **15 Years**

(21) Appl. No.: **29/714,216**

(22) Filed: **Nov. 21, 2019**

Related U.S. Application Data

(62) Division of application No. 29/597,104, filed on Mar. 14, 2017, now Pat. No. Des. 872,734.

(57) **CLAIM**

The ornamental design for a display screen with a graphical user interface, as shown and described.

DESCRIPTION

The FIGURE is a front view of a display screen with a graphical user interface showing our new design.

The broken lines showing a display screen and elements of the graphical user interface illustrate portions of the article, and form no part of the claimed design. The stippling shown in the FIGURE does not form a part of the claimed design.
